UNITED STATES PATENT OFFICE.

UNA ALLEN IMES AND HATTIE A. SKILLIN, OF AMES, COLORADO.

VEGETABLE-SLICER.

No. 853,796.

Specification of Letters Patent.

Patented May 14, 1907.

Application filed September 12, 1906. Renewed December 13, 1906. Serial No. 347,895.

To all whom it may concern:

Be it known that we, UNA ALLEN IMES and HATTIE A. SKILLIN, citizens of the United States, residing at Ames, in the county of San Miguel and State of Colorado, have invented new and useful Improvements in Vegetable-Slicers, of which the following is a specification.

This invention relates to vegetable slicers being designed especially for slicing potatoes and has for its objects to produce a comparatively simple, inexpensive device of this character in which the potato will at a single operation be cut into slices of a uniform size, one wherein the pressure head will conform readily to the material under treatment and to the movements of the operating lever, and one in which the slicing members may be conveniently interchanged for producing slices of varying sizes.

With these and other objects in view, the invention comprises the novel features of construction and combination of parts more fully hereinafter described.

In the accompanying drawings: Figure 1 is a longitudinal section through the center of the device. Fig. 2 is an enlarged detail view partly in section of the joint connection between the plunger rod and plunger. Figs. 3, 4 and 5 are plan views of the slicing members.

Referring to the drawings, 1 designates a body portion or ring provided between its ends with an internal horizontally projecting marginal flange 2, there being attached to the body 1 preferably at opposed points, a handle 3 and a vertically uprising bearing member or arm 4 to the upper end of which is pivoted one end of an operating lever 5 equipped at its other or free end with a hand-piece 6 and pivoted between its ends to the upper end of a plunger rod or stem 7, the normally lower end of which is provided with a socket 8 preferably of the form as seen in Fig. 2.

Removably seated in the body member 1 and resting at its lower end upon the flange 2 is a tubular receptacle or cup 9 designed to receive material to be sliced and in which there is arranged a movable pressure member or head 10 of substantially semi-spherical form presenting a flat normally lower face and provided with a projecting portion or stem 11

having at its upper end a reduced portion or nipple 12 shaped to conform to and designed to seat snugly in the socket 8, it being noted in this connection that the joint formed by the nipple fitting in the socket permits radial movement of the plunger rod 7 with the lever 5.

Screwed into the lower portion of the body 60 1 is a knife carrier or ring 13 designed to bear at its upper edge against the flange 2 and provided at its outer edge with a horizontal marginal flange 14 adapted to be grasped for screwing the ring in place, there being fixed 65 in said ring a plurality of cutting knives or blades 15 which as seen in Figs. 3 and 4 are arranged in spaced parallel relation and adapted for cutting a potato or the like in suitable slices. It is to be noted in this connection that the blades in Fig. 4 are spaced a greater distance apart than in Fig. 3 for thus cutting slices of greater thickness, while in Fig. 5 the blades are shown as intersecting each other for cutting the vegetable in strips.

In practice, the material to be sliced is placed in the receptacle 9 over the blades 15 which constitute a bottom for the receptacle. The operator then moves the free end of lever 5 downward thus causing the plunger 10 to force the vegetable or material from the receptacle between the blades 15, whereby it is cut into strips or slices. It may be mentioned that the device will be equipped with a plurality of the members or rings 13 in 85 which the blades are differently arranged and that these rings may be readily interchanged for effecting desired changes in the sizes or shape of the slices of material.

From the foregoing it is apparent that 90 there is produced a comparatively simple, inexpensive device admirably adapted for the attainment of the ends in view, it being understood that minor changes in the details herein set forth may be resorted to without 95 departing from the spirit of the invention.

Having thus described our invention, what we claim is:

In a device of the class described, an annular body portion provided with a handle and 100 an uprising bearing arm, an open ended receptacle having one end thereof seated in said body portion, a plunger movably arranged in the receptacle and having a stem,

an operating lever pivoted at one end in the bearing arm and provided between its ends with a stem operatively and detachably engaged with the first named stem, a ring 5 tapped into the body portion beneath the adjacent end of the receptacle and cutting blades sustained in the ring.

In testimony whereof, we affix our signatures in presence of two witnesses.

UNA ALLEN IMES.
HATTIE A. SKILLIN.
